UNITED STATES PATENT OFFICE.

JAMES F. BROWER, OF CORAL, MICHIGAN, ASSIGNOR OF ONE-HALF TO T. G. NORTHRUP, OF SAME PLACE.

MACHINE FOR FORMING THREADS ON SHEET-METAL CYLINDERS.

SPECIFICATION forming part of Letters Patent No. 247,533, dated September 27, 1881.

Application filed June 17, 1881. (No model.)

To all whom it may concern:

Be it known that I, JAMES F. BROWER, of Coral, Montcalm county, Michigan, have invented an Improvement in Machines for Forming Threads on Sheet-Metal Cylinders, of which the following is a specification.

The nature of this invention relates to certain new and useful improvements in the construction of devices employed in forming screw-threads upon the ends of sheet-metal cylinders, by means of which two or more sections of such pipes or cylinders may be readily joined together; and the invention consists in the peculiar construction of the parts and their various combinations, all as more fully hereinafter set forth.

Figure 1 is a vertical central longitudinal section. Fig. 2 is a side elevation of the standard with the gear-wheels removed. Fig. 3 is a horizontal section on line $x-x$, Fig. 1.

In the accompanying drawings, which form a part of this specification, A represents a proper base, from which rise the standards B and C, the upper portions of which are bifurcated. Between the bifurcations are placed the stationary boxes D D', which carry the shaft E. Upon one end of this shaft E is secured a corrugated or screw worm-wheel, F, while upon the opposite end of said shaft is secured the geared wheel G, there being a spring, a, interposed between the inner face of such wheel and the box D, as shown.

H and I represent sliding boxes capable of a vertical adjustment in their respective standards by means of the set-screws J J', which are tapped through the bars K, the said bars being secured to the upper ends of the standards. Within these boxes H I are secured the rocking boxes L, through which the upper shaft, M, is properly journaled. Upon one end of this shaft M is secured a similar worm-wheel, N, to that upon the shaft E, but with the pitch of its thread running in an opposite direction, while the other end of the shaft M carries a gear-wheel, O, and a crank-handle, P, by which motion is communicated to the parts. A spring,

b, is interposed between the wheel O and the box H.

In practice, the pipe or cylinder in which is to be formed the thread is slipped over the wheel F, abutting against the standard C, and the wheel N is gradually forced down upon it by means of the screw J', the shafts and their wheels being meanwhile rotated by means of the crank-handle, thus crimping a thread in 55 the pipe operated upon. The rocking boxes J prevent the binding of the shaft M in its adjustment, while the springs a and b allow the two worm-wheels N and F to properly engage with each other. 60

What I claim as my invention is—

1. In a screw-thread-bending machine, the base A, provided with bifurcated standards B C, in which are placed the bearings D H I L, and the shafts E M, in combination with the 65 stationary bearings D D', sliding bearings H I, rocking bearings L L, rotating shafts E M, and the spirally-grooved wheels F N, substantially as specified.

2. A device for forming screw-threads upon 70 sheet-metal cylinders, wherein the upper shaft is supported near its forward end within an oscillating box, which is, in turn, supported within a vertically-reciprocating box, substantially as and for the purposes described. 75

3. In a screw-thread-bending machine, and in combination with the standards B C and shafts E M, carrying the worm-wheels F N, the vertically-adjustable boxes H I, oscillating boxes L, gear-wheels O G, and the springs a b, 80 substantially as and for the purpose specified.

4. In a device for forming screw-threads upon sheet-metal cylinders, and in combination with the standards B C and shafts E M, carrying the worm-wheels F and N, the vertically-adjustable boxes H and I, and oscillating boxes L, substantially as and for the purposes herein set forth. 85

JAMES F. BROWER.
